(57) **CLAIM**

The ornamental design for an automobile headlight, as shown and described.

DESCRIPTION

FIG. 1 is a top, right, front perspective view of an automobile headlight;

FIG. 2 is a front view thereof;

FIG. 3 is a back view thereof;

FIG. 4 is a right side view thereof;

FIG. 5 is a top view thereof; and,

FIG. 6 is a bottom view thereof.

The broken lines in the drawings illustrate portions of the automobile headlight which forms no part of the claimed design.

The drawings and descriptions represent the left side embodiment. The claim is also for a mirror image right side embodiment.
